UNITED STATES PATENT OFFICE.

EDWIN D. BOLES AND EMIL A. UNTERSEE, OF BOSTON, MASSACHUSETTS, ASSIGNEES
TO GENERAL ELECTRIC COMPANY, A CORPORATION OF NEW YORK.

SPINNING-FRAME CONTROL.

1,358,409.

Specification of Letters Patent. Patented Nov. 9, 1920.

Application filed December 20, 1917. Serial No. 208,102.

To all whom it may concern:

Be it known that we, EDWIN D. BOLES and EMIL A. UNTERSEE, citizens of the United States, residing at Boston, county of 5 Suffolk, State of Massachusetts, have invented certain new and useful Improvements in Spinning-Frame Control, of which the following is a specification.

This invention relates to the control of 10 textile machinery such as spinning frames and the like and has for its object the provision of an improved means for controlling the speed of the driving motor in accordance with the movement of the ring rail of 15 the spinning machine, so as to maintain the tension of the yarn substantially constant.

Our invention relates more specifically to 20 the control of spinning machinery in which each spinning frame is driven by an electric motor. In a previous patent issued to Edwin D. Boles, No. 1,189,045, dated June 27, 1916, there is disclosed a form of device for causing the speed of the motor to vary in accordance with the rise and fall of the ring 25 rail. One of the leading features of this control is that the controller is driven by the electric motor and is independent of the spinning frame. One of the objects of this arrangement is to make the controller self- 30 contained and compact so that it will be entirely separate and distinct from the spinning frame itself. There are certain advantages, however, in driving the controller from the spinning machine. We have found that a controller so driven can be 35 made very simple and compact and be practically separate from the machine. Furthermore, we have found that it is desirable to completely inclose the controller thus 40 avoiding the dust and dirt incidental to the spinning room and also avoid the danger of its being tampered with by machine operators. Our improved controller is located 45 within the end shield of the motor thereby making the controller and the motor a self-contained unit connected with the machine only by the driving shaft and by a small shaft which operates the controller. We 50 also provide means whereby the controlling mechanism may be returned instantly to its initial position at the end of a doff, this being accomplished by having the member which gives the advance movement to the controller spring pressed to initial position,

there being provided means whereby when 55 the member is released from its holding pawl, it will return to its initial position and be in readiness for the next doff.

Other objects and purposes of our invention will appear in the course of the following specification in which we have shown our invention embodied in concrete form for purposes of illustration.

Referring to the drawing it will be seen that we have illustrated only such parts of 65 the spinning frame as seem essential for the disclosure of our invention, since spinning frames are old and well known and our invention does not depend in any way upon 70 the construction of the spinning machine.

In the accompanying drawing illustrating our invention, Figure 1 is a general view of a portion of the spinning frame, driving motor and controller. Fig. 2 is a fragmentary view of the motor showing the 75 controller in the end shield. Fig. 3 is a perspective view of the controller, and Fig. 4 is a detail of the controller parts.

Referring to Fig. 1, 10 represents the usual rollers, 11 the wire eye, and 12 the 80 ring rail on which is mounted the ring 13 carrying the traveler 14 of an ordinary ring spinning frame. In order to simplify the drawings as much as possible, we have simply shown the ring rail in a conventional manner 85 as being operated by a lever 15, pivoted at 16. One end of the lever is pivoted to the lower end of the rod 17, the upper end of which is secured to the ring rail so that the ring rail moves up and down with the rod 17. The 90 other end of the lever carries a weight 18 for raising the ring rail. The builder mechanism is also illustrated conventionally as consisting of a cam 19 driven through suitable gearing by an electric motor M. The 95 lever 15 is operated so as to raise the weight 18 by a flexible cord 20 having one end attached to a segmental arm 21 of the lever 15 while the other end of the cord is attached to one end of the lever 22, pivoted at 23, and 100 adapted to be rotated about its pivot by the cam 19. A rod 24, pivoted to the lever 22, extends upward and has in its upper end a roller 25 which engages the face of the cam 19, so that as the cam rotates the rod will be 105 forced downward so as to depress the end of the lever 22 to which the cord 20 is attached. The lever is raised by a weight

26 which holds the roller 25 in engagement with the face of the cam in the upward movement. In order to advance the ring rail we have provided means for gradually 5 lengthening the cord. This is done by having the cord mounted upon a shaft 27 driven by a worm wheel 28. This worm wheel is driven by a worm 29 mounted on a shaft 30, to the end of which is secured a ratchet 10 wheel 31. Coöperating with the ratchet wheel is a fixed pawl 32 so arranged that as the end of the lever carrying the ratchet wheel is raised by the weight 26 the ratchet wheel will be turned by engagement with the pawl 32 so as to rotate the gearing and 15 lengthen the cord. This will gradually lower the weight 18 and advance the ring rail in a well-known manner.

As a means for varying the speed of the 20 motor, we have illustrated a speed-varying device of the well-known brush-shifting type, although our invention is not necessarily limited to this particular speed-varying means. As shown the brushes 33 of the 25 motor are attached to a yoke 34 which is adapted to reciprocate back and forth to shift the brushes. This yoke is reciprocated by a mechanism which we shall now describe.

30 The brush-shifting mechanism or controller receives its motion from the spinning frame by a small shaft 35 which extends through the brush yoke 34 by way of an elongated opening 36. This shaft is 35 driven from the shaft on which the cam 19 is mounted by a sprocket chain 37 and sprocket wheel 38. On this shaft 35 is a cam 39 of substantially the same shape as the cam 19 and is rotated at the same rate 40 as the cam 19. The operating member for the brush yoke is a pivoted arm 40 which is directly connected with the brush yoke 34 by a positive driving or rigid connection in the form of an adjustable link 41. The connection between the arm 40 and the link 41 is made adjustable by means of the slotted connection 41'. The upper end of the arm 40 is provided with a roller 42 which engages the face of the cam 39 so that as the cam rotates it will force the arm to the left in Fig. 3 and, consequently, shift the brush yoke 34. The arm and brush yoke are returned by a spring 54 or other method. By this arrangement the brushes will be 55 shifted back and forth in accordance with the rise and fall of the ring rail. In order to advance the brushes in accordance with the advance of the ring rail, we provide means for lengthening the effective radius 60 at which the arm 40 acts on the leg 41. This we accomplish by means of a spring return member which comprises the spring 49, the rotatable ratchet disk 45, and the eccentric 43 secured to the shaft 44. The rotation of 65 the ratchet disk against the tension of the

spring 49 will vary the effective length of the arm 40 and thereby progressively shift the minimum speed of the speed range determined by the reciprocating movement of the arm 40. This disk is gradually rotated 70 by means of a pawl 46 which rests against the teeth of the ratchet wheel 45 and is reciprocated as the shaft 35 rotates. This is accomplished as shown in the drawing by mounting the pawl 46 on an arm 47 which 75 in turn is mounted on and operated by an eccentric 48 secured to the shaft 35. Upon each revolution of the shaft 35, therefore, the pawl will turn the ratchet disk one step. This ratchet disk is rotated against 80 the tension of a spiral spring 49, one end of which is secured to the disk while the other end is stationary. A pawl 50 holds the ratchet wheel in position against the spring tension. The ratchet disk is released 85 so as to permit it to return to its initial position in response to spring tension by lifting the two pawls 50 and 46. This is accomplished by arm 51 acting on both pawls and operated by a handle 53. 90

From the above it will be seen that as the ring rail rises and falls the brush yoke 34 will be positively shifted back and forth by the driving connection comprising the link 41 so as to increase and decrease the 95 speed of the motor over a definite range and at the same time the range is advanced by the rotation of the ratchet disk 45 operating against the spring tension so that when the doff is completed the controller 100 mechanism will return to its normal position by a simple movement of the handle 53. By referring to Fig. 2, it will be seen that the mechanism is so mounted and arranged as to be included in the end shield 52, there 105 being no connection between the controller within the end shield and the spinning machine other than the shaft 35. The motor and controller are, therefore, a self-contained unit which can be easily installed. 110

What we claim as new and desire to secure by Letters Patent of the United States, is,—

1. The combination with a ring spinning machine or the like, of an electric motor for driving the same, means for moving the brushes of the motor to vary its speed comprising a pivoted member connected to the brushes for moving the same back and forth and reciprocated with a fixed amplitude in 115 accordance with the periodic motion of the ring rail, and means comprising a member coöperating with said pivoted member for progressively shifting the position of the pivoted member to vary the minimum speed 120 of such fixed amplitude in accordance with the advance of the ring rail. 125

2. The combination with a ring spinning machine or the like, of an electric motor for driving the same, means for moving the 130

brushes of the motor to vary its speed comprising a pivoted member, means for reciprocating the same on its pivot in accordance with the rise and fall of the ring rail, and means for varying the effective radius of the pivoted member to shift the range of movement of the brushes in accordance with the advance of the ring rail.

3. The combination with a ring spinning machine or the like, of an electric motor for driving the same, means for moving the brushes of the motor to vary its speed comprising a pivoted member, means for reciprocating the same on its pivot in accordance with the rise and fall of the ring rail, and means advanced step by step in accordance with the advance of the ring rail for varying the effective radius of the pivoted member to shift the range of movement of the brushes in accordance with the advance of the ring rail.

4. The combination with a ring spinning machine or the like, of an electric motor for driving the same, means for moving the brushes of the motor to vary its speed comprising a pivoted member, means for reciprocating the same on its pivot in accordance with the rise and fall of the ring rail, a rotary member advanced step by step against a spring tension in accordance with the advance of the ring rail, and means operated by the rotary member for varying the effective radius of the pivoted member to shift the range of movement of the brushes in accordance with the advance of the ring rail.

5. The combination with a ring spinning machine or the like, of an electric motor for driving the same, means for moving the brushes of the motor to vary its speed comprising a pivoted member, means for reciprocating the same on its pivot in accordance with the rise and fall of the ring rail, means for adjusting the relation between the brushes and the pivoted member, and means for varying the effective radius of the pivoted member to shift the range of movement

of the brushes in accordance with the advance of the ring rail.

6. The combination with a ring spinning machine or the like, of an electric motor for driving the same, means for moving the brushes of the motor to vary its speed comprising a mechanism for varying the speed of the motor over a definite range in accordance with the rise and fall of the ring rail, a spring means for gradually advancing the range against the bias of the spring means for holding the range advancing means in its advanced positions, and means for disengaging the holding means to cause the range advancing means to return in accordance with the bias of the spring.

7. The combination with a ring spinning machine or the like, of an electric motor for driving the same and means for moving the brushes of the motor to vary its speed comprising a mechanism for varying the speed of the motor over a definite range in accordance with the rise and fall of the ring rail, a spring return ratchet disk coöperating with said mechanism and held in each position against the spring tension for gradually advancing the range and means for releasing the ratchet disk.

8. The combination with a ring spinning machine or the like, of an electric motor for driving the same and means for moving the brushes of the motor to vary its speed comprising a pivoted member, a cam driven by the machine for reciprocating the same on its pivot in accordance with the rise and fall of the ring rail, a spring returned ratchet disk rotated step by step by the machine and coöperating with said pivoted member to vary the relation between the member and the brushes to advance the range of the latter, and means for releasing the ratchet disk to permit it to return to its initial position.

In witness whereof, we have hereunto set our hands this eighth day of December, 1917.

EDWIN D. BOLES.
EMIL A. UNTERSEE.
